UNITED STATES PATENT OFFICE.

RICHARD LONG, OF STELAPOLIS, IOWA.

IMPROVEMENT IN BRIDGES.

Specification forming part of Letters Patent No. **146,397**, dated January 13, 1874; application filed September 13, 1873.

To all whom it may concern:

Be it known that I, RICHARD LONG, of Stelapolis, in the county of Iowa and State of Iowa, have invented a new and Improved Bridge, of which the following is a specification:

In the accompanying drawing, Figure 1 represents a side elevation, and Fig. 2 a cross-section, of my improved bridge on the line C C, Fig. 1.

Similar letters of reference indicate corresponding parts.

My invention relates to improvement in railroad and other bridges of shorter spans, with wooden arches; and consists in the use of stirrups suspended from the arches which carry the cross-beams, together with longitudinal stay-rods which connect the ends of the arches.

In the drawing, A represents the arch, made of bent planks, of suitable strength and size, which are covered with asbestos roofing, to be fully protected against the weather. Two or more arches, A, may be used, according to the width of the bridge. The ends of the arch rest in cast-iron shoes, B, on abutments C, and are rigidly connected by a strong stay-rod, G, which extends chord-like in longitudinal direction, passing above the cross-beams E. The rod G takes up the outward strain of the arch, and allows the sill to be dispensed with, which is desirable, as it requires splicing, and rots out too quickly. The cross-beams E are supported by a number of stirrups, F, which are made of round iron, suspended from the top of arch A by

nuts and washers. The legs of the stirrups F, toward the center of the arch, are perpendicular, and the others converge toward some common center. The legs of the central stirrup F are both inclined radially. The stirrups F are arranged symmetrically on both sides of the central axis of the arch, and are bent around the cross-beams with rounded-off corners, to prevent any weakening of the rod. The lower side of the cross-beams E is correspondingly grooved, and provided with similarly-grooved washer-plates E'. The sleepers, planking, &c., are placed in the usual manner on the cross-beams E, which are also diagonally braced, to increase the strength of the bridge. The railing H is attached to the stirrup-rods by staples, in a very simple manner.

The bridge may be used for railroad or common purposes, only that in the former cases a greater number of stirrups and cross-beams is required.

Having thus described my invention, I claim as new and desire to secure by Letters Patent—

The combination of arches A, having end shoes B and connecting stay-rods G, with cross-beams E, washers E', and stirrups F, arranged symmetrically with the central axes of the arch, and forming an improved bridge for railroad and other purposes, substantially as set forth.

RICHARD LONG.
